[57] CLAIM

The ornamental design for a roof balcony, as shown and described.

DESCRIPTION

FIG. 1 is a perspective view of a roof balcony showing
my new design;

FIG. 2 is a front elevational view thereof;

FIG. 3 is a top plan view thereof;

FIG. 4 is a cross sectional view taken along line 4—4 of
FIG. 2;

FIG. 5 is a cross sectional view taken along line 6—6 of
FIG. 4;

FIG. 6 is a cross sectional view taken along line 6—6 of
FIG. 2.

The broken line showing the building and sidewalk of the several figures is for illustrative purposes only and forms no part of the claimed design.
